UNITED STATES PATENT OFFICE.

HOWARD B. VANNOTE, OF HASBROUCK HEIGHTS, AND SAMUEL A. NEIDICH, OF
EDGEWATER PARK, NEW JERSEY.

MACHINE FOR REWINDING PAPER AND OTHER FABRICS.

1,294,576.

Specification of Letters Patent. Patented Feb. 18, 1919.

Application filed July 30, 1917. Serial No. 183,529.

To all whom it may concern:

Be it known that we, HOWARD B. VANNOTE and SAMUEL A. NEIDICH, citizens of the United States, residing, respectively, at Hasbrouck Heights, county of Bergen, State of New Jersey, and Edgewater Park, county of Burlington, State of New Jersey, have invented certain new and useful Improvements in Machines for Rewinding Paper and other Fabrics, of which the following is a specification.

This invention relates to machines for rewinding paper and other fabrics.

Our object is the provision of a novel expandable and contractible drum, in a rewinding machine, having means whereby the drum will automatically contract in exact proportion to the thickness of the material wound, thereby compensating for the variation in diameter of the drum, with its windings of paper or fabric, which would otherwise occur and insuring uniform length for the successive sheets comprising the web which is wound upon the drum so that upon subsequent severance, the sheets will all be of the same length.

Our invention contemplates the provision of means whereby the drum may be expanded or contracted to bring it to any desired initial diameter and automatic means adjustable at will while the drum is rotating for contracting the drum in diameter at predetermined times in exact proportion to the thickness of the material being wound thereon. The surface or periphery of the drum is of such a construction that accommodation is given for the excess material in the under layers as the drum contracts and successive windings are placed therearound.

In all forms of our invention the drum has a peripheral winding surface composed of a plurality of separated sections or segments which are preferably slate or bars extending lengthwise of the drum. These sections are mounted for outward and inward movement in a radial direction and novel means are provided for simultaneously and quickly moving the sections inwardly or outwardly to thereby evenly expand or contract the drum.

The sections or segments being separated or spaced apart, the excess material of the paper or fabric which is being wound on the drum forms loops between the opposing faces of the sections as the drum contracts, thereby taking care of this excess and pre-

venting any bunching of the material which would interfere with the evenness of successive windings.

The drum is rotated in any suitable manner, as, for instance, by a belt, and it is mounted on a shaft. Novel means operatively connecting the shaft with the drum provide for the automatic contraction of the drum at predetermined times, the basic principle being that the drum is expansible and contractible by changes of relationship between the speed of the drum and that of the supporting shaft therefor, controlled at will while the drum is rotating.

In the following description there are set forth, and in the accompanying drawings shown, certain mechanisms or means for accomplishing the automatic expansion and contraction of the drum in the manner above set forth. We are aware, however, that other means could be used for the accomplishment of this purpose and the disclosure of certain means for that purpose is therefore to be considered as illustrative, rather than descriptive, of the scope of the invention.

In the accompanying drawings:

Figure 1 is a side elevation of the invention, shown in connection with a carrier and cutter;

Fig. 2 a plan view thereof;

Fig. 3 a detail side elevation of the invention;

Fig. 4 a detail front view showing one section or segment, and the means for moving it inwardly or outwardly;

Fig. 5 a detail side elevation of the automatic controlling mechanism;

Fig. 6 an elevation thereof with certain parts in section; and

Fig. 7 a detail showing how the layers of paper or fabric form a loop between adjacent sections or segments.

In Figs. 1 and 2, the machine of the present invention which appears at the left, and is generally designated 1, is shown in connection with a carrier belt, suitably supported, and a paper cutting knife, generally designated 2. After the paper has been rewound on the machine 1, the layers are cut across by a knife and the bunch of sheets removed from the drum and placed on the carrier belt of the machine 2, said belt conveying them to the cutting knife which severs them into proper lengths.

The parts of the rewinding machine are supported by a frame 3. The paper or other

fabric is carried by a roll 4 which is suitably revolvably supported at 5 so that the web may be freely taken off on to the drum 6.

The drum 6 may be driven by any suitable means as, for instance, a belt 7 passing around the pulley portion 8 and operated from a pulley 9 on a suitably driven countershaft 10. Fixed to the drum 6 are hollow trunnions or stub shafts 11 supported in the standards of the frame 3 and revolvably supporting the drum as shown in Fig. 6. The drum comprises, in addition to the heads or parts 6, sections or segments 12 which are preferably of wood and are mounted for radial movement, each section being carried by stems 13 slidable in boxings or sleeves 14 fixed to the interior of the heads 6 and radially arranged. A shaft 15 is mounted in the hollow stub shafts 11 and provided with right and left hand screw threads 16 and 17. Collars 18 and 19 which are internally screw threaded to match the screw threads 16 and 17, respectively, are mounted on said screw threaded parts of the shaft 15 and are connected to the segments 12 by links 20 and 21 which are pivoted at 22 and 23, respectively. When the shaft 15 is turned in one direction, the collars 18 and 19 will approach each other to thereby contract all of the segments 12 in a uniform manner thus uniformly decreasing the diameter of the drum. When shaft 15 is turned in the opposite direction, the collars 18 and 19 will move away from each other and uniformly expand the segments 12 to thereby uniformly expand the diameter of the drum.

A crank, not shown, may be applied to the end of the shaft 15 for the purpose of manually expanding or contracting the drum 40 to bring it to the desired diameter prior to the winding of the paper or other fabric thereon. When set, the automatic mechanism, now to be described, provides for the automatic contraction of the segments, and 45 consequently, the diameter of the drum, on each revolution of the drum, with adaptability for changing the adjustment at will while the drum is rotating.

As shown in Fig. 7, the segments 12 are 50 separated by a space 24 which accommodates the excess of paper or fabric appearing at 25 of those layers 26 which have been wound upon the drum. Consequently, as the drum successively contracts with the additional 55 windings of paper therearound, there is no interference with the smooth and even laying of the outermost sheets of paper.

Secured to the stub shaft 11 is a detent disk or wheel 27 which has a notch 28. Fast 60 on the shaft 15 is a ratchet wheel 29. Pivoted at 30 to the frame 3 or to a strap 31 carried thereby is a pawl arm 32, actuated by a spring 33 which draws it toward the ratchet wheel 29 and detent disk 27. A detent arm 34 having a roller 35 travels on the

periphery of the disk 27 and, once during each revolution of said disk and the drum 6, enters the notch 28, allowing the pawl arm 32 to engage the ratchet wheel 29. The depth to which the pawl arm 32 will enter 70 the teeth of the ratchet wheel 29 and the period it will remain in engagement therewith is regulated by a thumb screw 36 carried by the arm 32 and arranged in connection with a scale 32^a.

Normally, because the shaft 15 is fixed in relation to the segments 12, the ratchet wheel 29 turns with the detent disk 27, the roller 35 riding on the periphery of the disk 27. Once during each revolution of the 80 drum 6, the detent roller 35 enters the notch 28, thereby for a predetermined period, enabling the spring 33 to draw the arm 32 forward so that it will engage ratchet wheel 29. The continued revolution of the drum 6, 85 while the ratchet wheel 29 is arrested, causes the collars 18 and 19 to approach each other, as they turn on the screw-threaded portions 16 and 17, thereby uniformly contracting the segments 12 and decreasing the diameter 90 of the drum 6. The extent of the contraction of the drum is determined by the period the roller 35 remains in the notch 28, which, in turn, is regulated by the screw 36. The parts are so timed that the contraction compensates for the thickness of the paper wound on the drum, as each succeeding winding is laid thereon. The screw 36 is adapted to be turned while the drum is rotating, if desired, to change the adjustment. 95 Consequently, it is not necessary to stop the drum when a different extent of contraction of the drum is desired. Such change of contraction can be had either while the drum is stationary or while it is in rotation.

Carried by the drum is a scale 37, Fig. 1, with which a pointer 38 pivoted to a spoke of the drum at 39, cooperates. A link 40 is pivotally connected to the pointer and to one of the segments 12. The pointer 38 and scale 37 indicate the circumference of the drum at any given time.

A suitable clamp, not shown, is used for securing one end of the paper to the drum. A counting device or register, not shown, 115 may be used in a well known manner to indicate the number of sheets wound on the drum.

A brake may be employed for quickly arresting the drum, as indicated by the brake beam 41, brake shoe 42 carried thereby and lever 43 for operating the brake beam.

A gear train such as shown at 53, 57, 59, 60 may be used for contracting the drum shown in Figs. 3 to 7, inclusive. The gears 125 of this train may be interchangeable with gears of a slightly different number of teeth to adjust the rate of amount of contraction of the drum.

The invention may be carried out in other 130

constructions than that heretofore set forth and shown in the drawings, the principle of the invention being the automatic contraction of the diameter of the drum by the employment of means adjustable at will either when the drum is stationary or rotating adapted to periodically change to the desired extent the relative speeds of the drum and the central controlling shaft as, for instance, by retarding the central shaft as desired once during each revolution of the drum.

Having thus described our invention, what we claim as new and desire to secure by Letters Patent is:—

1. In a machine for rewinding paper or other fabrics, an expandable and contractible rewinding drum having a central shaft, and means adjustable at will while the drum is rotating, said means coöperating with said shaft and being adapted for changing the diameter of the drum.
2. In a machine for rewinding paper or other fabrics, an expandable and contractible rewinding drum having a central shaft, and automatic means adjustable at will while the drum is rotating, said means coöperating with said shaft adapted for contracting the diameter of the drum.
3. In a machine for rewinding paper or other fabrics, an expandable and contractible rewinding drum having means embodying a device which is stationary in relation to the drum and adjustable at will while the drum is rotating, said means being adapted for automatically contracting the drum successively to a predetermined extent to compensate for the constantly increasing thickness of the windings thereon.
4. In a machine for rewinding paper or other fabrics, an expandable and contractible

rewinding drum having a rotary controlling member, and means embodying a device which is stationary in relation to the drum and adjustable at will while the drum is rotating, said means being adapted for expanding or contracting the drum by effecting a change in the relative speed of the drum and rotary controlling member. 45

5. In a machine for rewinding paper or other fabrics, an expandable and contractible rewinding drum having means adjustable at will while the drum is rotating for automatically contracting said drum to a degree proportionate to the varying thickness of 55 the material wound, to compensate for such thickness.

6. In a machine for rewinding paper or other fabrics, a rewinding drum having a peripheral portion comprising radially movable sections, and means embodying a device which is stationary in relation to the drum and adjustable at will, adapted for automatically contracting the drum at each revolution. 60

7. In a machine for rewinding paper or other fabric, the combination with an expandable and contractible drum, of a rotatable shaft, operative connections between said shaft and the winding portion of the 70 drum, a detent disk connected to the drum, a ratchet wheel connected to said shaft, a pawl adapted to engage the ratchet wheel, a detent arm coöperating with the detent disk, and an adjustable connection between 75 the pawl and detent arm, whereby the duration of engagement of the pawl and ratchet wheel may be controlled.

In testimony whereof, we hereunto affix our signatures.

H. B. VANNOTE.
S. A. NEIDICH.
